(57) **CLAIM**

The ornamental design for a dental air/water syringe, as shown and described.

DESCRIPTION

FIG. 1 is a perspective view of a dental air/water syringe; FIG. 2 is a left-side elevation view thereof; FIG. 3 is a right-side elevation view thereof; FIG. 4 is a front elevation view thereof; FIG. 5 is a rear elevation view thereof; FIG. 6 is a top plan view thereof; and, FIG. 7 is a bottom plan view thereof. All features in phantom line are for the purpose of illustrating environmental structure and form no part of the claimed subject matter. Color and texture may or may not form part of the claimed design or designs without departing from the design disclosed.
